Inventor:

William C. White,

by *Albert S. Davis*

His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

SIGNALING SYSTEM.

Application filed January 31, 1919, Serial No. 274,288. Renewed August 14, 1923.

To all whom it may concern:

Be it known that I, WILLIAM C. WHITE, a citizen of the United States, residing at Schenectady, county of Schenectady, State 5 of New York, have invented certain new and useful Improvements in Signaling Systems, of which the following is a specification.

This application is a continuation in part 10 of my prior application, Serial No. 46,769, filed August 23, 1915.

My present invention relates to a signaling system, and more especially to means for transmitting wireless signals.

One of the objects of my invention is to 15 provide means for producing continuous electrical waves and means for varying the amplitude of the waves thereby produced. A more particular object of my invention is to provide means for varying the amplitude 20 of or modulating the continuous waves in accordance with variations in sound waves.

In carrying my invention into effect I 25 preferably employ an electron discharge device for producing continuous electrical waves in an antenna. If such a device is supplied with a direct current source of constant potential and suitable circuit connections made thereto it may be made to produce continuous electrical waves of practically constant amplitude in the antenna. If, however, the potential supplied thereto is variable, the amplitude of the waves produced will vary in accordance with the potential variations in the source of supply. 30 Hence if the potential of the supply source is caused to vary in accordance with variations in sound waves the amplitude of the waves produced may be caused to vary accordingly.

40 In my prior application, Serial No. 46,769, filed August 23, 1915, I have claimed broadly the method of modulation which consists in varying the potential supplied to the electron discharge device and the apparatus for carrying out that method. I have also claimed specifically one form of my invention in which both a constant potential and a variable potential are supplied to the electron discharge device. My present 45 application is directed to a second form of my invention in which the only potential supplied to the electron discharge device is a variable signaling potential.

The features of my invention which I be-

lieve to be novel are set forth with particularity in the appended claims. The invention itself, however, both as to its organization and method of operation, together with further objects and advantages thereof, will best be understood by reference to the following description taken in connection with the accompanying drawings in which Fig. 1 illustrates diagrammatically one way in which my invention may be carried into effect, and Fig. 2 shows a modification thereof. 55

As indicated in Fig. 1 of the drawings, the means for producing continuous electrical waves in the antenna 1 comprises an electron discharge device 2 consisting preferably of a highly evacuated envelope having therein 70 a cathode 3 of filamentary form, an anode 4, and a conducting body 5, which is preferably in the form of a grid interposed between the cathode and anode. Current for the operation of the device is supplied to 75 the circuit between the cathode and anode by means of the secondary 6 of the transformer 7. The circuit between cathode and anode also contains an inductance 8 which is inductively related to the inductance 9 80 in the antenna. The circuit which includes the cathode 3 and the grid 5 contains an inductance 10 which is inductively related to the inductance 11 in the antenna. The coupling between 8 and 9 is preferably close, 85 while that between 10 and 11 may in some cases be made very loose. The battery 12 may be employed for adjusting the normal potential of the grid 5 to a value which is most suitable for the efficient operation of 90 the device. The circuit which comprises the secondary 6, the inductance 8, the anode 4, and the cathode 3, for convenience of description, I designate the plate circuit. The circuit which comprises the grid 5, inductance 10, and cathode 3, I designate the grid 95 circuit. Any desired means may be employed for heating the cathode 3 to incandescence. In the present case I have shown a battery 13 for this purpose. 100

When current in the proper direction is supplied to the plate circuit of the device 2 by means of the secondary 6 of the transformer 7, the device 2 will produce continuous electrical waves in the antenna. When 105 the direction of the current is such that the anode 4 is positive, current flows in the plate circuit and a potential is induced in coil 9

and in the antenna. This produces a corresponding induced potential in coil 10 and varies the potential of the controlling grid 5. This change in grid potential in turn produces a variation in the plate circuit. When the potential induced in the grid circuit causes the grid to become more negative the current flowing in the plate circuit is decreased while an induced potential which 5 makes the grid more positive increases the current flow in the plate circuit. These variations in the current in the plate circuit produce an alternating current in the antenna, the frequency of which will be the 10 same as the frequency to which the antenna is tuned. The amplitude of the high frequency waves thus produced in the antenna will, among other things, depend upon the potential produced in the secondary 6 of the 15 transformer 7, and the amplitude of the oscillations will vary in accordance with variations in this potential. In order to vary the potential in the plate circuit of the device 2 in accordance with variations in 20 sound waves, the current produced in the local circuit of a telephone transmitter 14 is impressed through a transformer 15 upon the grid circuit of an electron discharge device 16, the construction of which is similar 25 to that of the device 2. The plate circuit of the device 16 is supplied with current from a direct current source 17 and the current flowing in the plate circuit of the device 16 will be a pulsating current which 30 varies in accordance with the variations in the current in the local circuit of the telephone transmitter 14. This pulsating current flows through the primary 18 of transformer 7 and produces a low frequency 35 alternating modulating current in the secondary 6 of the transformer 7. This alternating current will of course vary in accordance with the variations in the telephone current. As a result the high frequency current 40 produced by device 2 will vary in amplitude in accordance with variations in the amplitude of the telephone current. When the direction of the potential in the plate circuit of device 2 is such that the anode 45 becomes negative no current will flow in the plate circuit of the device 2, and hence no high frequency oscillations will be produced. As a result waves will be produced only during every other half cycle of the 50 low frequency signaling current produced in the secondary 6 of the transformer 7. It is possible to transmit speech by means of waves of this nature though the articulation may not be as perfect as it would be in 55 case both half waves of the low frequency current were employed for producing high frequency current.

By the arrangement shown in Fig. 2 the disadvantage pointed out above may be avoided. In this case, as indicated, two

electron discharge devices 19 and 20 are employed, each of which is connected to the antenna 1 in a manner similar to the connection of device 2, as shown in Fig. 1. The inductance 8 is common to the plate circuits 70 of both devices 19 and 20, but separate coils 21 and 22 are used for the grid circuits of these devices, these coils being oppositely coupled to the antenna coil 11. In this case the telephone current from transmitter 14 75 is impressed directly upon the plate circuits of the two devices by means of the transformer 23, although, if desired, an amplifier may be used in the same manner as indicated in Fig. 1. The current produced in the secondary of transformer 23 will of course be a low frequency alternating current of the same nature as that produced in the secondary 80 6 of the transformer 7 in the arrangement shown in Fig. 1. It will be noted, 85 however, that devices 19 and 20 are oppositely connected to the secondary of transformer 23 so that during one half wave of the low frequency alternating current one of these devices will operate to produce high 90 frequency current while during the other half wave the second device will operate to produce high frequency currents. Thus both positive and negative half waves of the low frequency alternating signaling current will 95 be effective in controlling the production of high frequency oscillations and the oscillations produced will always vary in accordance with the variations in the low frequency current.

It will be apparent that with either of the arrangements described the amplitude of the high frequency waves produced in the antenna will fall to zero when the amplitude of the signaling wave becomes zero. The 105 wave produced by the system which I have described is in effect a continuous wave which is modulated by the signaling current. It may properly be said of such a wave that it is damped by the modulating wave only in 110 contradistinction to a modulated wave produced by the spark system or other system which is not adapted to produce undamped waves.

The system which I have described also 115 is of particular advantage for use in carrying on duplex signaling because of the fact that high frequency waves are supplied to the antenna only while the transmitter 14 is active. At other times the antenna is 120 in condition for receiving signals without disconnecting the transmitting apparatus.

If desired the coil 11 may be omitted and the coils 10, 21 and 22 be inductively related to coil 9. In most cases, however, 125 I find that the arrangement shown is preferable as by connecting the circuits in this way the amplitude of the oscillations produced is greater than if coil 10 were coupled to coil 9. This may be due to the fact that 130

the phase relation of currents in the grid and plate circuits with this arrangement is somewhat different than when coils 10, 21 and 22 are directly coupled to coil 9 and that this difference causes an increase in the amplitude of the oscillations produced.

In the operation of the system which I have described when the potential induced in the plate circuit by reason of the action 10 of the sound waves in the telephone transmitter is such as to cause an increase in the current in the plate circuit, there will be a corresponding increase in the current in the antenna. As a result the current induced in the grid circuit will increase correspondingly. The potential upon the grid will be increased and a further increase in the amplitude of the plate current will be effected thereby. With the proper adjustment 20 this accumulative effect may be useful to a large extent in increasing the variations in the amplitude of the waves produced in the antenna. Under some conditions, however, this effect may become so great as to impair the articulation of the speech or other sounds transmitted.

While I have shown and described two modifications of my invention illustrating its utility for wireless telephony, I do not 30 wish to be limited to the particular arrangements shown as it will be apparent that many variations in the connections used may be made without departing from the scope of the appended claims, and that it may 35 equally well be used for the wireless transmission of other signals than sound waves, or for the transmission of sound or other signals through wire circuits.

What I claim as new and desire to secure 40 by Letters Patent of the United States, is:—

1. In a high frequency signaling system the method of transmission which consists in producing a low frequency alternating modulating signal wave, generating to the 45 exclusion of other high frequency waves, a high frequency wave which when produced will vary in accordance with said low frequency modulating wave, which is damped by the modulating wave only, and 50 which falls to zero when the amplitude of the modulating signal wave becomes zero and in transmitting said high frequency wave.

2. In a high frequency signaling system 55 the method of transmission which consists in producing a low frequency alternating modulating signal wave, controlling by means of said signal wave the generation of a high frequency wave and thereby generating to the exclusion of other high frequency waves a high frequency wave which when produced will vary in accordance with said low frequency modulating wave, which is damped by the modulating wave only, and 65 which falls to zero when the amplitude of

the modulating signal wave becomes zero and in transmitting said high frequency wave.

3. The method of operating a signaling system which comprises an electron discharge device having grid and plate circuits coupled together for producing oscillations which consists in supplying to the plate circuit of said device a low frequency signaling current and thereby causing said device 70 to produce high frequency oscillations which vary in amplitude in accordance with the amplitude of the signaling current and which fall to zero when said signaling current becomes zero, and in transmitting the 75 high frequency oscillations thus produced.

4. In a high frequency signaling system which comprises an electron discharge device, the method which consists in producing a low frequency alternating signaling 85 wave, applying this low frequency wave to the electron discharge device to produce a high frequency wave whose amplitude varies in accordance with said low frequency signaling wave, and which falls to zero when 90 the amplitude of the signaling wave becomes zero and in transmitting said high frequency wave.

5. In a high frequency signaling system which comprises an electron discharge device, the method which consists in producing a low frequency alternating signaling wave, applying this low frequency wave to the electron discharge device and thereby controlling the production of a high frequency 100 wave which when produced will vary in accordance with said low frequency signaling wave, and which falls to zero when the amplitude of the signaling wave becomes zero and in transmitting said high frequency 105 wave.

6. In a high frequency signaling system, the combination of a source of low frequency alternating modulating signal waves, a high frequency alternating current generator 110 adapted to generate sustained undamped oscillations, means for controlling the action of said generator so that when oscillations are generated they will vary in amplitude in accordance with said low frequency modulating waves and fall to zero when the amplitude of the modulating wave becomes zero and means for transmitting said oscillations to the exclusion of other high frequency oscillations.

7. In a high frequency signaling system, the combination of a source of low frequency alternating modulating signal waves, means comprising an electron discharge device for producing sustained undamped oscillations, means for controlling the action of said oscillation producing means so that when oscillations are produced thereby they will vary in amplitude in accordance with said low frequency modulating waves, and 130

fall to zero when the amplitude of the modulating waves becomes zero, and means for transmitting said oscillations to the exclusion of other high frequency oscillations.

- 5 8. In a high frequency signaling system, the combination of a source of low frequency alternating modulating signaling waves, an electron discharge device having coupled grid and plate circuits for producing high 70 frequency oscillations, means for supplying to the plate circuit of said device low frequency signaling waves, and thereby causing said device to produce high frequency oscillations which vary in amplitude in accordance with the amplitude of the signaling waves, and which fall to zero when the amplitude of said signaling waves becomes zero, and means for transmitting the high frequency oscillations thus produced.
- 10 9. The combination with a thermionic oscillator having a pair of anode circuits, of telephonic means supplying energy to said anode circuits which respectively select the positive and negative energy delivered by 80 said means.

- 15 10. The combination with a thermionic oscillator having a pair of anode circuits, of a transformer whose secondary is connected to said anode circuits, and means for supplying modulated energy to said transformer including a source of continuous current, and means for varying the current from said source in accordance with sound waves.

- 20 11. The combination with an electron discharge oscillator having a pair of plate circuits, of means for supplying energy modulated in accordance with sound waves to said plate circuits in such a way that energy components of one polarity are selected by one 90 plate circuit and energy components of the opposite polarity are selected by the other plate circuit.

- 25 12. The method of electrically transmitting sound waves, which consists in producing electrical energy modulated in accordance with sound waves and comprising components of opposite polarities, converting the modulated energy into different dissimultaneously existing groups of oscillations 100 whose envelope is uninterrupted and representative of the sound waves, and impressing energy of the oscillations upon a transmitting medium.

- 30 13. The method of electrically transmitting sound waves, which consists in producing electrical energy modulated in accordance with sound waves and comprising components of opposite polarities, impressing the components of different polarities upon different oscillators to produce different groups of oscillations, varying in amplitude in accordance with sound waves, and impressing energy of the oscillations of the different groups upon a transmitting medium.

- 35 14. The method of electrically transmit-

ting sound waves, which consists in producing electrical energy modulated in accordance with sound waves, amplifying said energy in form having components of different polarities, converting the amplified modulated energy into different groups of oscillations whose envelope is uninterrupted and representative of the sound waves, and impressing energy of the oscillations of the different groups upon a transmitting medium.

40 15. The combination with a pair of oscillators, of means for producing energy modulated in accordance with sound waves and having positive and negative components, means for impressing the components of different polarities upon different of said oscillators, and means for impressing energy of the different groups of oscillations upon a transmitting medium.

45 16. The combination with a pair of oscillators producing oscillations of the same frequency, of means for producing energy modulated in accordance with sound waves and having positive and negative components, 90 means for impressing the components of different polarities upon different of said oscillators, and means for impressing energy of the different groups of oscillations upon a transmitting medium.

50 17. The combination with a pair of thermionic oscillators, of means producing electrical energy modulated in accordance with sound waves and having components of different polarities, means for supplying the components of different polarities to different of said oscillators, whereby the envelope of the successive groups of oscillations is continuous, and means for impressing energy of the successive groups of oscillations upon a transmitting medium.

55 18. In a high frequency signaling system the method of transmission which consists in producing a low frequency alternating modulating signal wave, generating to the exclusion of other high frequency waves and solely by energy supplied by said signal wave, a high frequency wave which when produced will vary in accordance with said low frequency signal wave, and in transmitting said high frequency wave.

60 19. In a high frequency signaling system the method of transmission which consists in producing a low frequency alternating modulating signal wave, controlling by means of said signal wave the generation of a high frequency wave which is produced solely by energy supplied by said signal wave and thereby generating to the exclusion of other high frequency waves a high frequency wave which when produced will vary in accordance with said low frequency signal wave and in transmitting said high frequency wave.

65 20. The method of operating a signaling 130

system which comprises an electron discharge device having grid and plate circuits coupled together for producing oscillations which consists in supplying to the plate circuit of said device a low frequency signaling current only and thereby causing said device to produce high frequency oscillations which vary in amplitude in accordance with the amplitude of the signaling current and in transmitting the high frequency oscillations thus produced.

21. In a high frequency signaling system which comprises an electron discharge device, the method which consists in producing a low frequency alternating signaling wave, applying this low frequency wave only to the electron discharge device to produce a high frequency wave whose amplitude varies in accordance with said low frequency signaling wave and in transmitting said high frequency wave.

22. In a high frequency signaling system which comprises an electron discharge device, the method which consists in producing a low frequency alternating signaling wave, applying this low frequency wave to the electron discharge device and thereby controlling the production of a high frequency wave which is produced solely by energy supplied by said signaling wave, and which when produced will vary in accordance with said low frequency signaling wave, and in transmitting said high frequency wave.

23. In a high frequency signaling system the combination of a source of low frequency alternating modulating signal waves, a high frequency alternating current generator adapted to generate sustained undamped oscillations, means for controlling the action of said generator so that when oscillations are generated they will be produced solely from energy supplied by said low frequency signal waves and will vary in amplitude in accordance with said low frequency waves and means for transmitting said oscillations to the exclusion of other high frequency oscillations.

24. In a high frequency signaling system, the combination of a source of low frequency alternating modulating signal waves, means comprising an electron discharge device for producing sustained undamped oscillations, means for controlling the action of said oscillation producing means so that when oscillations are produced thereby they will be produced solely from energy supplied from said low frequency source and will vary in amplitude in accordance with said low frequency modulating waves, and means for transmitting said oscillations to the exclusion of other high frequency oscillations.

25. In a high frequency signaling system, the combination of a source of low frequency modulating signaling waves, an electron discharge device having coupled plate and grid circuits for producing high frequency oscillations, means for supplying to the plate circuit of said device low frequency signaling waves only and thereby causing said device to produce high frequency oscillations which vary in amplitude in accordance with the amplitude of the signaling wave, and means for transmitting the high frequency oscillations thus produced.

26. In a high frequency signaling system the method which consists in producing a low frequency signal wave, generating solely by means of energy supplied by said low frequency signal wave a high frequency wave which varies in amplitude in accordance with said low frequency wave and transmitting said high frequency wave.

27. The method of operating a signaling system which comprises an electron discharge device having grid and plate circuits coupled together for producing oscillations which consists in causing said device to produce high frequency oscillations solely by means of energy supplied by a low frequency signaling wave and transmitting the oscillations thus produced.

28. The method of operating a signaling system which comprises an electron discharge device having grid and plate circuits coupled together for producing oscillations which consists in supplying to the plate circuit of said device a low frequency signaling wave only and thereby causing the production of high frequency oscillations by means of energy derived solely from said low frequency signaling wave and transmitting the high frequency oscillations thus produced.

29. In a high frequency signaling system the combination of a source of low frequency alternating modulating signal waves, a high frequency alternating current generator and means for causing said generator to produce high frequency oscillations solely from energy supplied by said low frequency source.

30. In a high frequency signaling system the combination of a source of low frequency alternating modulating signal waves, an electron discharge device having plate and grid circuits coupled together for producing high frequency oscillations, and means for causing said device to produce high frequency oscillations solely from energy supplied by said low frequency source.

In witness whereof, I have hereunto set my hand this 30th day of January, 1919.

WILLIAM C. WHITE.
